UNITED STATES PATENT OFFICE.

ARTHUR B. DODD, OF CAMDEN, NEW JERSEY.

WATER-FAUCET.

1,216,963.

Specification of Letters Patent. Patented Feb. 20, 1917.

Application filed February 25, 1916. Serial No. 80,503.

To all whom it may concern:

Be it known that I, ARTHUR B. DODD, a citizen of the United States, residing at Camden, in the county of Camden and State 5 of New Jersey, have invented new and useful Improvements in Water-Faucets, of which the following is a specification.

This invention relates to dispensing faucets, the object in view being to produce 10 a faucet embodying a novel construction and relative arrangement of parts for seating and unseating the controlling valve of the faucet, whereby the valve may be operated both by hand and by pressure exerted on 15 a certain element thereof by a glass or any other receptacle while positioned under the discharge end of the faucet. The construction which will be hereinafter particularly described enables a person to fill, for example, a glass or tumbler by holding the 20 same under the discharge nozzle of the faucet and without requiring the use of the other hand.

With the above and other objects in view, 25 the invention consists in the novel construction, combination and arrangement of parts, as herein described, illustrated and claimed.

The accompanying drawing represents a 30 vertical longitudinal section through a faucet embodying the present invention.

The body of the faucet indicated at 1 is of the usual tubular formation and is shown as terminating in a downwardly deflected spout 2, the nozzle being threaded at 35 3 to enable the same to be attached to any desired supply such as a pipe or reservoir.

Arranged centrally within the tubular body 1 is a valve seat 4 and coöperating therewith is a valve 5, the latter being fixedly mounted upon and carried by a valve 40 stem 6 which is of sufficient length to work through openings in the top and bottom walls of the body 1 and project beyond the same so as to be connected at one end to 45 a hand lever 7 arranged on the upper side of the faucet, said lever being pivotally connected at 8 to the valve stem 6 and being pivotally attached at 9 to a post 10 extending upwardly from the top of the faucet.

50 Another post 11 extends downwardly from the bottom of the faucet and has connected thereto by a pivot 12 a second lever 13 which underlies the faucet body and is connected by a pivot 14 to the lower ex-

tremity of the valve stem 6. At its free end 55 the lever 13 is provided with a notch 15 or projections 16 in spaced relation to each other thereby enabling any receptacle 17 such as a glass, tumbler or the like to be placed under the discharge nozzle of the 60 faucet with the rim or edge of the receptacle engaging the free end of the lever 13.

The valve 5 is held normally seated and returned to its closed position by means of 65 a single valve seating spring 18 located interiorly of the faucet body. In order to accommodate the valve stem 6 and provide for packing the same, the body 1 is provided with upwardly and downwardly extending tubular bosses 19 and 20 which are 70 threaded to receive packing nuts or glands 21. Within each gland is a packing ring 22 of rubber or other flexible material which by the tightening of the nuts or glands 21 may be compressed as tightly as may be 75 necessary around the stem 6 to prevent leakage.

In operation, the receptacle 17 is placed 80 under the discharge nozzle of the faucet and in engagement with the free end of the lever 13. Then an upward pressure of the receptacle 17 results in unseating the valve 5 and permitting a flow of liquid through 85 the faucet. As soon as the receptacle 17 is lowered, the flow is cut off by reason of the fact that the valve 5 is automatically 90 returned to its closed position by means of the spring 18. Additionally, when both hands of the operator are free, the receptacle 17 may be held under the faucet in 95 one hand and the valve opening lever 7 may be manipulated by the other hand. The faucet may thus be operated in either of two ways according to the convenience or requirement of the operator.

Having thus described my invention, I 95 claim:—

The combination with a tubular faucet body having upwardly and downwardly extending posts and upwardly and downwardly extending tubular bosses, of a valve seat within said tubular body, a valve coöperating therewith, a single valve stem extending on both sides of the valve body through said upwardly and downwardly extending tubular bosses and projecting beyond the latter, a manually operable lever 100 connected with the upper post and the upper 105

extremity of said valve stem, and a second valve operating lever connected with the lower post and with the lower extremity of said valve stem, and a single valve closing spring encircling the valve stem and operating to simultaneously return both of said levers to their normal positions.

Copies of this patent may be obtained for five cents each, by addressing the "Commissioner of Patents, Washington, D. C."

In testimony whereof I affix my signature in presence of two witnesses.

ARTHUR B. DODD.
